[57] CLAIM

The ornamental design for a cradle for a portable telephone set, as shown and described.

DESCRIPTION

FIG. 1 is a front elevational view of a cradle for a portable telephone set showing our new design;

FIG. 2 is a rear elevational view thereof;

FIG. 3 is a top plan view thereof;

FIG. 4 is a bottom plan view thereof;

FIG. 5 is a right side elevational view thereof, the left side being a mirror image thereof; and

FIG. 6 is a front, top and right side perspective view thereof.

FIG. 1

FIG. 2

FIG. 3

FIG. 4

FIG. 5

FIG. 6
